SINGLE SLEEVE VALVE ENGINE

Edward Leslie Gilbert, Fort Bayard, N. Mex.

Application November 20, 1933, Serial No. 698,908
Renewed May 7, 1935

1 Claim (Cl. 123—81)

This invention relates to single sleeve valve engines and is an improvement over the type of engine set forth in my U. S. Letters Patent granted March 4, 1930 and numbered 1,749,701 and has for 5 the primary object the provision of a simplified sleeve operating mechanism which reduces the number of parts and permits the cylinders of the engine to be arranged in closer relation, consequently permitting a shorter crank shaft to be 10 employed and materially reduces end thrusts from the sleeves of the cylinder and provides a quieter operating engine.

With these and other objects in view this invention consists in certain novel features of construction, combination and arrangement of parts to be hereinafter more fully described and claimed.

For a complete understanding of my invention, reference is to be had to the following description and accompanying drawings, in which

20 Figure 1 is a side elevation illustrating an engine with improved sleeve valves and showing the compactness of the engine.

Figure 2 is a transverse sectional view taken on the line 2—2 of Figure 1 showing the operating 25 mechanism for the sleeve valve.

Figure 3 is a fragmentary horizontal sectional view showing the sleeve valves and their operating mechanisms.

Figure 4 is a detail sectional view taken on the 30 line 4—4 of Figure 1.

Figure 5 is a side elevation partly in section illustrating one of the sleeve valves.

Figure 6 is an end elevation illustrating the same.

35 Figure 7 is a plan view illustrating an attaching ring employed upon the sleeve valve.

Figure 8 is a perspective view illustrating a guide for the attaching ring.

40 Figure 9 is a plan view illustrating one of the eccentric straps and showing a part of the valve operating means as forming an integral part thereof.

Figure 10 is an end elevation illustrating the same.

45 Figure 11 is a fragmentary plan view illustrating a cam shaft.

Referring in detail to the drawings, the numeral 1 indicates the cylinders of the engine mounted to a base 2 provided with a crank case 3. The 50 cylinders are suitably water-jacketed and equipped with removable heads 4 each provided with a depending portion 5 extending into a cylinder and spaced from the walls of the latter to form a guide for the upper end of a sleeve 55 valve 6. The cylinders are provided with in-

take and exhaust ports 7 of substantially triangular shape and the sleeve valves 6 are provided with intake and exhaust ports 8 to be moved into and out of registration with the ports 7 of the cylinders. Spark plugs 9 are mounted in spark plug openings 10 formed in the depending portions 5 for igniting the fuel within the cylinders. Pistons 11 are reciprocally mounted in the cylinders with the sleeve valves interposed between the pistons and the walls 10 of the cylinders. A crank shaft 12 is journaled in bearings carried by the motor base and are connected to the pistons 11 by connecting walls 13. The sleeve valves extend below the lower ends of the cylinders into the base 2 and are provided 15 adjacent their lower ends with annular grooves 14 to receive valve operating means 15.

The foregoing description sets forth broadly the type of engine forming the subject matter of my patent heretofore referred to.

20 A cam shaft 16 driven from the crank shaft is journaled to the base 2 and is located at one side of the crank shaft and in a plane slightly above the latter and has formed integrally therewith cams 17. The cams are designed for actuating the valve operating mechanism 15 and the latter each include a sleeve-like element 18 journaled upon its respective cam and has formed integrally therewith an upwardly directed arm 19 pivoted to spaced ears 20 formed on one side of 25 an annular member 21 fitted within the groove 14 of the sleeve valve and the latter by being so connected to the cam receives during the rotation of the cam reciprocatory movement for controlling the intake and exhaust ports 7 of the respective 30 cylinder. The member 21 opposite to the ears 20 is provided with a guide lug 22 slidable between the forked portion 23 of a guide 24 depending from the top wall of the base 2.

The sleeve-like member 18 mounted upon the 40 cam is provided with a guide lug 25 operating between a forked portion 26 of a depending guide 27 and the latter is secured to the top wall and one of the side walls of the base 2.

Extending laterally from the lower end of each 45 of the sleeve valves is a lug 28 to which is journaled one end of a connecting arm 29, the opposite end of which is offset downwardly and pivoted to spaced ears 30 formed on the sleeve-like member 18. The connecting arm 29 includes intermediate and end sections and said sections are pivotally connected, as shown at 31. The pivots between the sections are reversely arranged to each other so as to cooperate in forming a universal construction within the connecting arm. 50 55

During the movement of the sleeve-like member 18 by its respective cam the connecting arm 29 will oscillate the sleeve valve which with the reciprocation of the latter will effectively control the intake and exhaust ports of the cylinder.

The valve operating means having thus been described, it will be seen that besides efficiently operating the sleeve valve it consists of a minimum number of parts and that the parts are so designed that the operation of the sleeve valve will be carried out with quietness and efficiency besides the guides provided in the mechanism will resist end thrusts developed by the sleeve valve consequently rendering successful operation of the engine over a longer period of time and further with the present valve operating mechanism permits the cylinders of the engine to be arranged in closer relation and thereby permit the use of a shorter crank shaft as well as a shorter cam shaft.

Having described the invention, I claim:

An internal combustion engine including a base carrying a cylinder having intake and exhaust ports and an ignition means for said cylinder, a sleeve valve having intake and exhaust

ports slidably and rotatably mounted in the cylinder for controlling the intake and exhaust ports of said cylinder, a piston slidable in said sleeve, a crank shaft journaled to the base, means connecting the piston to the crank shaft, a cam shaft journaled to the base and driven from the crank shaft, an eccentric on the cam shaft, a sleeve-like member journaled on the eccentric of the cam shaft, an arm integral with the sleeve-like member, an annular member rotatably secured to the sleeve valve and pivoted to said arm whereby said sleeve valve may be reciprocated by the rotation of the cam shaft, a lug carried by the sleeve valve, a connecting arm journaled to said lug and pivoted to the sleeve-like member and including a universal construction within itself to impart oscillatory movement to the valve sleeve during the latter's reciprocal movement, a guide secured to the base, a guide lug on the annular member and received by the guide, a second guide carried by the base, and a second guide lug upon the sleeve-like member and received by the second-named guide.

EDWARD LESLIE GILBERT.
